CLAIM

The ornamental design for a viscous fluid discharge gun, as shown and described.

DESCRIPTION

FIG. 1 is a front view of a viscous fluid discharge gun of the present invention.

FIG. 2 is a rear view thereof.

FIG. 3 is a top plan view thereof.

FIG. 4 is a bottom view thereof.

FIG. 5 is a right side view thereof.

FIG. 6 is a left side view thereof.

FIG. 7 is a perspective view thereof; and,

FIG. 8 is a reference view thereof, showing the occasion of use.

The features shown in broken lines depict environmental subject matter only and form no part of the claimed design.
